CLAIM

The ornamental design for a steam air fryer, as shown and described.

DESCRIPTION

FIG. 1 is a front perspective view of the steam air fryer; FIG. 2 is rear perspective view thereof; FIG. 3 is a front view thereof; FIG. 4 is a rear view thereof; FIG. 5 is a left side view thereof; FIG. 6 is a right side view thereof; FIG. 7 is a top view thereof; and, FIG. 8 is a bottom view thereof.

In some implementations, the steam air fryer as shown in FIGS. 1, 6, and 7 includes a set of vents extending from a right side to a top side. In some implementations, a front side of the steam air fryer, as shown in FIGS. 1, 3, 5, and 6 includes a control panel. In some implementations, the top side of the steam air fryer, as shown in FIGS. 1, 3, 4, 6, and 7 includes a locking feature.

The broken lines shown in the figures show features of the steam air fryer that form no part of the claimed design.
